CONTAINER FOR STORING DENTURES OR THE LIKE

Ted Seller, Birch Lane, Greenwich, Conn. 06830

Filed Feb. 13, 1967, Ser. No. 5,802

Term of patent 14 years

(Cl. D86—10)

FIG. 1 is a top plan view of a container for storing dentures or the like;

FIG. 2 is a bottom plan view;

FIG. 3 is a side elevational view;

FIG. 4 is an end elevational view;

FIG. 5 is an elevational view partially in section taken on the line 5—5 of FIG. 1; and

FIG. 6 is a fragmentary view partly in section taken on the line 6—6 of FIG. 1.

I claim:

The ornamental design for a container for storing dentures or the like, as shown.
